UNITED STATES PATENT OFFICE.

DAVID R. ROSEBROUGH, OF CASEY, ILLINOIS.

CLOTHES-PIN.

No. 808,687.

Specification of Letters Patent.

Patented Jan. 2, 1906.

Application filed November 23, 1904. Serial No. 234,074.

To all whom it may concern:

Be it known that I, DAVID R. ROSEBROUGH, a citizen of the United States, residing at Casey, in the county of Clark and State of Illinois, 5 have invented certain new and useful Improvements in Clothes-Pins; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in clothes-pins; and the object of the invention is to produce a simple and efficient device which will securely hold clothes to a line.

My invention consists, further, in various 20 details of construction and in combinations and arrangements of parts, which will be hereinafter fully described and then specifically defined in the appended claim.

My invention is illustrated in the accompanying drawings, which, with the letters of reference marked thereon, form a part of this application, and in which drawings—

Figure 1 is a perspective view showing the device as applied to a clothes-line. Fig. 2 is 30 an enlarged detail perspective view; and Fig. 3 is a side elevation.

Reference now being had to the details of the drawings by letter, A designates a wire which is bent at its longitudinal center forming a V-shaped portion A', which is slightly concaved longitudinally. The strands of the 35 wire which are thus bent form a V-shaped portion, and said strands flare at the ends of

the V-shaped portion and are bent at angles to each other, as at B, and downwardly curved 40 and provided with parallel portions. The straight parallel portions of the strands of the wire are twisted together, as at D, while the parts of each strand adjacent to its end are outwardly flaring and turned laterally into eyes 45 at their ends:

In applying my clothes-fastener it will be observed that the twisted portion co-operates with the loop A' and is slightly flexible, adapted to hold the clothes against a clothes-line in 50 the manner shown in Fig. 1 of the drawings, thereby making a simple and efficient device which may be readily applied and removed from a line.

Having thus fully described my invention, 55 what I claim as new, and desire to secure by Letters Patent, is—

A clothes-fastener comprising a wire which is bent at its longitudinal center forming a V-shaped shank portion, the opposite strands 60 forming the longitudinal edges of which are slightly curved, the strands of wire at the flaring ends of said V-shaped portion being curved away from said V-shaped portion and having parallel portions which are spaced 65 apart a short distance, thence twisted together, and flaring arms extending over the strands forming said V-shaped portion and the extreme ends of said arms laterally bent and turned into eyes, as set forth. 70

In testimony whereof I hereunto affix my signature in presence of two witnesses.

DAVID R. ROSEBROUGH.
